S. SARGENT.

Coal Oil Lantern.

No. 33,312.

Patented Sept. 17, 1861.

UNITED STATES PATENT OFFICE.

S. SARGENT, OF WATERTOWN, ASSIGNOR TO HIMSELF AND A. P. KNAPP, OF NEEDHAM, MASSACHUSETTS.

IMPROVEMENT IN COAL-OIL LANTERNS.

Specification forming part of Letters Patent No. 33,312, dated September 17, 1861.

To all whom it may concern:

Be it known that I, S. SARGENT, of Watertown, in the county of Middlesex and State of Massachusetts, have invented a new and Improved Lantern for Burning Coal-Oils and other Oils Containing a Large Proportion of Carbon; and I do hereby declare that the following is a full and exact description thereof, reference being had to the accompanying drawings, making part of this specification—

Figure 1 being a side elevation of the lantern complete; Fig. 2, a central vertical section thereof; Fig. 3, a transverse section of the lantern-body in the plane indicated by the line *xx*, Fig. 1; Fig. 4, a plan of the lamp detached; Fig. 5, a transverse section of the lantern-body, looking upward in the plane indicated by the line *yy*, Fig. 1.

Like letters designate corresponding parts in all the figures.

As in constructing lamps for burning the particular oils referred to in this specification the great difficulties to overcome arise from the necessity of a large, even, and uninterrupted supply of oxygen to the burner, which difficulties are increased when the lamps are designed to be portable on account of the necessary derangements of the supply of air in the draft, by unsteadiness of motion, and subjecting the lamps more to sudden blasts of air, so in constructing lanterns for burning these oils all the difficulties named are rather increased than diminished, and the additional difficulties arising from the use of the lantern body or case and holding the whole beneath the hand are required to be overcome.

My present improvements have principal reference to overcoming these additional difficulties, while any improvements in the lamps of the lanterns may be employed in connection with them.

I employ for the lantern-body a glass globe *A*, a base *B*, top *C*, and cap *Q*, all to be carried by a bail or handle *G* and constructed in any usual or convenient manner. The general construction of the lamp *D* may also be of any style or plan desirable, and the burner *S* may be provided with the most efficient improvements for burning the oils. A chimney *E* is also employed, being directly within the glass globe *A*. The lamp-base *b* fits closely within the base *B* of the lantern-body, and it is confined therein by two spring-catches *c c*,

attached to the lamp and springing over a flange *e* on the inside of the base *B*, all substantially as is shown in Fig. 2. Any equivalent arrangement for the purpose may be employed.

The first part of my improvement is intended for the purpose of enabling the wick *H* to be regulated from the outside of the lantern-body without taking out the lamp, and in connection therewith the proper arrangements of the lantern-body to admit that improvement. I make the rod or shaft *L* by which the wick is moved long enough to reach out through the base *B* of the lantern-body when the lamp is inserted therein, so that its head *f* may be turned with as perfect readiness as that of a simple lamp; but in order to allow this extension of the shaft *L* out through the lantern-body provision must be made for reaching the aperture which it occupies in the lantern-body when inserting the lamp, and for withdrawing it from said aperture when the lamp is taken out of the lantern-body, and the side of the lantern-body must also be kept closed, so as not to disturb the draft to the burner. To accomplish these purposes I form a vertical slot *d* in the side of the lantern-body *B* wide enough to admit the shaft *L* and reaching from the bottom of the lantern-body to the necessary height. A larger opening *g*, Fig. 2, is also made in the foot *a* of the lantern to allow the passage of the head *f* of the shaft *L* up and down. This slot allows the free insertion and withdrawal of the shaft *L*. To close this slot after the insertion of said shaft *L* I employ a plate *M*, which fits closely upon the base *B* and slides between lips *h h*, so that it may readily be shut over the slot *d*, as shown by black lines, or be moved away therefrom, as shown by red lines in Fig. 1. Thus the whole purpose intended is perfectly accomplished. The draft to the lamp-burner is ordinarily admitted through holes *ll* in the sides or periphery of the base *B* of the lantern-body, so that the ordinary motion in walking will not impede the progress of the air into the lantern; but when the lantern is suddenly lowered, the foot *a* thereof interrupts the steady flow of the air through the holes *ll*, and for the moment would cause the lamp to smoke, unless some provision were made to prevent it. To accomplish this I perforate the flange *b* of the lamp with small apertures *ii*, as seen in Figs. 2 and 4. These

apertures admit air from below the lamp, where its flow is rather increased than impeded by the sudden descent of the lantern. It may be remarked here that to properly regulate the flow of air to the burner, and to counteract the rush of too much air suddenly to the burner, it is necessary that it should be admitted through many small apertures instead of through one or a few large ones. It is also necessary, to perfectly prevent smoking, that the air should be admitted evenly and equally to all sides of the burner; and I find that on account of the exposure of lanterns to swift and sudden motions and strong gusts of wind some provision is required to secure the equilibrium of draft on all sides. The next part of my improvement has this purpose for its object. I employ several vertical division-plates N N, secured radially to the inside of the periphery of the base B, so as to divide the draft-space between this base and the lamp-body D into as many distinct compartments, as shown in Figs. 2 and 3. This simple device keeps the draft divided, directs the separate portions straight upward, and prevents an undue accumulation or pressure of air on either side by eddies thereof or by blasts of wind. Instead of attaching the division-plates N N to the base B of the lantern-body, they might be attached to the lamp-body D.

Another part of my improvement consists in the employment of a horizontal plate P, extending outward from the lamp-burner S just above the perforations therein, which admit the air to the flame inside when constructed and operating as hereinafter set forth. The construction and use of this plate will be understood after explaining the action of the draft-air inside of the lantern. The main portion of the air admitted into the base of the lantern is to support the combustion of the oil at the burner, but another portion is intended to proceed directly upward into the glass globe A, outside of the chimney E, the use of which circulation of air may be said to be to keep the lantern as cool as possible and to facilitate the clearing of the draft at the top of the lantern, and by consequence to increase its efficiency. Another use of this passage of air is to furnish a sort of regulator against a too great sudden supply of air to the burner itself by affording an outlet to an undue supply thereof. To effect these desired results there is a space n, Fig. 2, left outside of the plate P to allow a regular circulation of the air outside of the chimney E. The plate P is also perforated with fine holes, as seen most clearly at m, Fig. 4, so that as it arrests sufficient air passing upward to supply the burner its perforations prevent a sudden overaccumulation and pressure of air from a too great supply thereof from below by allowing the excess to quickly escape upward into the globe of the lantern. The device therefore may be termed the "draft-governor." A

thin plate T of metal is located just above the draft-escape apertures o o, and at the bottom of the convex cap Q of the lantern. It does not quite cover the whole top of the lantern; but there is a narrow annular space p, Fig. 2, around its edge, so as to allow a circulation of the draft-air above it in the cap Q and escape therefrom, and thereby prevent heating the air therein very hot. At the same time this shield-plate produces all the good effect of interposing a non-conducting space to prevent the conduction of undue heat upward. The plate T may be attached to the lantern-top C by narrow supporting strips r r, so as to close as little of the space p as may be.

Another part of my improvement consists in the employment of a "guard-cylinder" or annular plate R around the top C of the lantern, and outside of the draft-escape apertures o o, leaving a space between it and the lantern-top of, say, a fourth of an inch in thickness all round, open at the bottom, as at s, Fig. 2, and terminating in perforations t t, Figs. 2 and 5, at the top, through the flange by which the guard-cylinder is attached to the lantern-top. This cylinder or plate accomplishes several useful purposes. First, it affords a shield or guard to the draft-escape apertures o o to prevent gusts of air impeding the escape of the draft. It likewise assists the draft by furnishing a circulation of air upward in the space between it and the lantern-top, and producing thereby an exhaustive action upon the lantern-draft. Finally, by mingling cold outward air with the escaping hot air of the draft, it reduces the same to a temperature low enough not to discommode the hand above by which the lantern is carried.

Another part of my improvement is a draft-collector consisting of an annular band or cylinder u, secured to the foot a of the lantern, but open at the top and reaching upward about as high as the upper draft-apertures l l, substantially as shown, leaving a space between it and the base of the lantern for the free admission of air to the said draft-holes. The object of this is to collect sufficient air on a sudden raising of the lantern to continue a sufficient draft through the holes l l for the moment, and thus prevent smoking from such a movement.

What I claim as my invention, and desire to secure by Letters Patent, is—

The arrangement and combination of the device for enabling the wick to be regulated outside of the lantern, the perforations i i in the base-flange of the lamp D, the draft-collector u, division-plates N N, perforated regulating-plate P, and guard-cylinder R, in the manner and for the purposes herein specified.

S. SARGENT.
